UNITED STATES PATENT OFFICE.

CHARLES E. OWENS, OF GRAHAM, NORTH CAROLINA, ASSIGNOR OF ONE-HALF TO
J. HARVEY WHITE, OF GRAHAM, NORTH CAROLINA.

TEMPLE.

1,103,074.

Specification of Letters Patent.

Patented July 14, 1914.

Application filed December 8, 1913. Serial No. 805,244.

To all whom it may concern:

Be it known that I, CHARLES E. OWENS, a citizen of the United States, and a resident of Graham, county of Alamance, and 5 State of North Carolina, have invented a new and useful Improvement in Temples, of which the following is a specification.

The object of my invention is to improve a temple so that it will not mar or injure 10 a fabric being woven when a gout or stub comes up in the filling, but will always act so as to keep the fabric properly distended while being woven. This and other 15 objects are accomplished by my invention, one embodiment of which is hereinafter set forth and shown in the accompanying drawing, in which,

Figure 1 is a plan view of my improved temple. Fig. 2 is an elevation, partially 20 in section, the section being taken substantially on the line 2—2 of Fig. 1, looking in the direction of the arrows. Fig. 3 is a sectional view, taken on the line 3—3 of Fig. 1, looking in the direction of the arrows. Fig. 4 is an end elevation. Fig. 5 is a side elevation of an end of my improved temple.

Throughout the various views of the drawings, similar reference characters designate similar parts.

My improved temple 1 has the usual casting 2, spring pressed bar 3 mounted therein, and spiked roller 4 mounted in a case 5 carried by this bar 3. The novelty of my 35 invention resides in the means for mounting this roller so that it may be raised when necessary to preserve the cloth, or for any other reason. This is accomplished in the following manner.

The case 5 has an integral lower jaw 6 of the conventional kind on which is slidably mounted the upper jaw 7 in which 40 the spiked roller 4 is mounted. The top of this jaw 7 has a suitable rub plate 8

of wood, or other material on which rests 45 one end of a leaf spring 9, the other end of which is fixed to the casting 2.

The spring pressed bar 3 also carries a suitable guiding lug 10, on which the jaw 7 is mounted, and this jaw 7 carries a suitable 50 guide 11 which enters a corresponding slot in the lower jaw 6 so that the upper jaw 7 may shift vertically against the tension of the spring 9 whenever occasion requires, as above set forth, the lugs 10 and 11 with 55 their interengaging parts forming guides. When this structure is in use, the spiked roller may be cleaned from time to time without changing a nut or screw or the use of any tool so the weaver can always 60 keep the temple in proper condition without additional aid. In view of these advantages, the temple herein described permits both quantity and quality to be increased.

While I have shown and described one embodiment of my invention, it is obvious 65 that it is not restricted thereto, but is broad enough to cover all structures that come within the scope of the annexed claim.

What I claim is:

In a temple, a casting, a spring pressed bar slidably mounted in said casting, the lower jaw fixed to said bar, an upper jaw slidably mounted on said bar and provided 75 with a roller, and a leaf spring secured to said casting and pressing said upper jaw against the lower jaw, so that when the temple is in use and undue thickness of cloth passes between the jaws, the upper 80 jaw may be raised, or when the device is to be cleaned the spring may be raised and the upper jaw removed.

CHAS. E. OWENS.
